UNITED STATES PATENT OFFICE.

JOSEPH C. ZUMWALT, OF CLAY CENTER, NEBRASKA.

DISK SHARPENER.

Application filed August 19, 1926. Serial No. 130,826.

This invention relates to new and useful improvements in sharpening devices, and particularly to sharpening devices for the disks of agricultural implements such as 5 harrows, cultivators, and the like.

The principal object of the invention is to provide a device by means of which the disks of an agricultural machine may be sharpened automatically, while the machine is in 10 motion.

Another object is to provide a sharpening device of this character which can be easily and quickly applied to the implement in 15 position to sharpen the edge of a disk, when the machine is moved, and the disk is set in rotation, such device being movable into position for sharpening each of the disks in succession.

Other objects and advantages will be apparent from the following description when taken in connection with the accompanying drawing.

In the drawing:

Figure 1 is a top plan view of a portion of 25 a disk cultivator, showing the invention in sharpening position with relation to one of the disks.

Figure 2 is a vertical sectional view, on the line 2—2 of Figure 1, showing the invention in elevation.

Figure 3 is a transverse sectional view, on the line 3—3 of Figure 1, looking toward the sharpening disk.

Figure 4 is a perspective view of another 35 form of sharpening disk, which is octagonal in outline.

Figure 4 is a similar view of a further form which is square in outline.

Referring particularly to the accompanying drawing, 10 represents a portion of the frame of a disk cultivator having disks 11 properly mounted thereon, and in connection with which the present invention is used.

The invention includes an elongated bar 45 12 having a hook 13 on one end. Slidably longitudinally on the bar is a sleeve 14, and formed on one side of the sleeve is an arm 15, said arm being spaced a short distance away from the edge of the bar. Disposed 50 through the arm is a bolt 16, and mounted on the bolt, between the arm and the edge of the bar, is a metal sharpening disk 17, such disk being shown in circular form in Figures 1 to 3, inclusive, and as octagonal 55 in Figure 4, and square in Figure 5. The edge portion of the disk 17 overlaps the edge

of the bar a short distance, as clearly seen in the top plan view Figure 1, whereby the peripheral edge of the disk cooperates with the adjacent side face of the bar to form 60 a wedge opening into which the edge portion of the cultivator disk is adapted to move, while said disk is in rotation. A nut 18 is engaged on the other end of the bolt 16 to hold the disk 17 against rotation. The 65 hook end of the bar is engaged around the axle or shaft of the disk to be sharpened, as shown in the drawing, and a strong length of timber, or a metal pipe 10' placed across the frame of the cultivator, on which the 70 other end of the bar 12 is adapted to rest. The device is so positioned that the edge of the cultivator disk lies within the angle between the sharpening disk 17, and the adjacent face of the bar 12. The machine is then 75 driven forwardly for a distance approximately fifty or a hundred yards, with the result that the edge of the cultivator disk will be properly sharpened against the peripheral face of the disk 17. When one 80 disk has been sharpened, the device is removed and replaced in the same relation to the next disk, and the machine moved the proper distance to produce the required 85 sharpening of the disk. The above operation is continued until all of the cultivator disks have been sharpened. When the disk 17 shows signs of becoming dull, the operator loosens the nut 18, and rotates the disk a short distance to expose an unused portion 90 of the periphery thereof for action upon the edge of a cultivator disk.

Ordinarily, in disk harrows or disk cultivators, the disks are arranged in gangs, with the concave sides of the disks of each gang 95 disposed toward the outside of the machine. The operation above described applies to the disks of one gang, but when the disks of the other gang are to be sharpened, the sleeve 14 is removed and reapplied to the bar 12, in 100 reverse position, that is with the disk 17 extending from the other side of the bar, and arranged therebelow. This is made necessary to permit the disk 17 properly engaging the edges of the other disks. A set 105 screw 19 is engaged through the sleeve 14, and into biting engagement with the bar, whereby to properly hold the sleeve so that the disk 17 will be disposed in the desired 110 relation to the edge of the cultivator disk.

While I have illustrated the disk sharpening disk as having its sharpening edge ar-

ranged at right angles to the planes of the side faces thereof, I wish it understood that such sharpening edges may be beveled to present a smaller sharpening face to the edge of the cultivator disk.

The bar 10' is suspended from the frame by the chains 11', whereby to support the weight of the bar 12, and to prevent sagging of the bar 10'.

10. What is claimed is:

An agricultural disk sharpener comprising a flat bar having a hook on one end lying in the plane of the bar, a sleeve slidable on the bar having a terminally apertured arm

formed on its upper side and extending 15 transversely of the upper edge of the bar and thence longitudinally in parallel relation to the bar, means for adjustably maintaining the sleeve at different positions on the bar, and a sharpening element disposed 20 transversely beneath said arm, and clamping means through the aperture of the arm and through the sharpening element, a portion of the periphery of the sharpening element overlapping the upper edge of said bar. 25

In testimony whereof, I affix my signature.

JOSEPH C. ZUMWALT.
